(57) **CLAIM**

The ornamental design for a foot rest pillow, as shown and described.

DESCRIPTION

FIG. 1 is a perspective front view of the foot rest pillow, showing my new design;

FIG. 2 is a right side view with the left side view being a mirror image thereof;

FIG. 3 is a rear view thereof;

FIG. 4 is a front view thereof;

FIG. 5 is a top view thereof;

FIG. 6 is a bottom view thereof; and,

FIG. 7 is a perspective front view showing the foot rest pillow in an alternate closed configuration.

In the drawings, the broken lines represent portions of the foot rest pillow that form no part of the claimed design.
